UNITED STATES PATENT OFFICE.

EDWARD B. STRONG, OF DETROIT, MICHIGAN.

CAR-AXLE BOX.

SPECIFICATION forming part of Letters Patent No. 320,412, dated June 16, 1885.

Application filed April 29, 1885. (No model.)

To all whom it may concern:

Be it known that I, EDWARD B. STRONG, of Detroit, in the county of Wayne and State of Michigan, have invented new and useful 5 Improvements in Lubricating Car-Axes; and I do hereby declare that the following is a full, clear, and exact description thereof, reference being had to the accompanying drawings, which form a part of this specification.

10 This invention relates to certain new and useful improvements in the means and method of lubricating railroad-car journals within their boxes by the employment of capillary attraction.

15 The novelty consists in the peculiar combinations and the construction and arrangement of parts hereinafter more fully described and claimed.

20 Figure 1 is a vertical cross-section of a car-axle box, showing the axle journaled within the box, the brass bearing above the journal, and the wedge interposed between the top of the brass bearing and the top of the box. Fig. 2 is a longitudinal vertical central section of 25 the same.

25 In the drawings, A represents the box, which is of any of the known or approved forms of construction. B is the journal of the car-axle within said box. C is the brass bearing, 30 saddled upon the top of the journal-bearing; and D is the wedge interposed between the top of said brass bearing and the top of the box. E are wicks, preferably formed each in one length, sufficient to reach far enough below 35 the axis of the car-axle to meet the oil found in the well of the axle-box, as shown in both figures, although it will not be necessary for the ends of such wicks to extend clear to the bottom of the well, as there shown, as such

40 well may be filled with waste saturated with oil, when it would only be necessary for the ends of the wick to extend far enough downward into such waste as to attract and take up the oil.

45 In the drawings presented, channels *a* are cut or formed laterally across the top of the brass bearing, and the wicks lie in these channels. Orifices or perforations *b*, are formed in and through the brass bearings, 50 affording the only means of communication through which the oil carried up by the wicks

can find its way to the top of the journal of the car-axle, the rapid revolution of which has a tendency to create a vacuum in these passages *b*, which causes the oil carried up by 55 the wicks to be frequently discharged through such passages.

It will be noticed that in the drawings the top surface of the brass bearing is convex from end to end, the highest point being in the 60 longitudinal center of such bearing. It will also be noticed that the wedge is perfectly flat, with its top and bottom sides parallel, so that when the box and journal stand level (as when not in operation) the weight imposed is 65 directly upon the center of the brass bearing; but when these parts are in use—for instance, as under a car in motion—the box will rock slightly upon the top of the brass, and at each oscillation the tendency will be to squeeze or 70 press the oil in the wicks alternately and force such oil more freely to flow through the passages leading through the brass bearing. Where this form of application is shown, recesses *c* are formed across the lower face of the 75 wedge coincident with the recess formed in the top of the brass bearing to receive the wick. It is not essential, however, that the construction and application herein shown should be at all times used in order to produce 80 a perfect oiling of the journal by capillary attraction, as the same result would be produced were the wick to be carried up and across the top of the wedge and interposed between the top of such wedge and the top of 85 the box, so long as coincident perforations through the wedge and the brass bearing would permit the oil to be discharged onto the journal.

What I claim as my invention is—

90 1. The combination, with a channelled brass bearing, and with lubricating-wicks arranged upon either side of an oval center thereof, of a rocking block adapted to compress the wicks alternately, as and for the purposes set forth. 95

2. In a car-axle box, and in combination therewith and with a car-axle journal, a brass bearing having one or more lateral channels formed in its upper face, communicating with passages leading downward through such bearing, 100 and a wedge between such bearing and the top of the box, the parts being constructed

and operated substantially as and for the purposes set forth.

3. In a car-axle box, the bearing-brass C, having transverse channels *a* arranged upon either side of an oval center, and having perforations *b*, combined with the wicks E and the wicks D, having recesses *c*, and resting

upon the oval center of the brass, as and for the purpose specified.

EDWD. B. STRONG.
